METHOD OF AND APPARATUS FOR THE
REPRODUCTION OF SOUND

James E. Dickert, Highland Park, Ill., assignor to
World Broadcasting System, Inc., New York,
N. Y., a corporation of Delaware

Application December 7, 1938, Serial No. 244,436

31 Claims. (Cl. 179—1)

The invention relates generally to the audible reproduction of message matter or sound such as instrumental or vocal music, talking, or combinations thereof, and more particularly it relates to those systems of audible production and reproduction of message matter of this character which involve the transmission of energy representing a function of the original sound-intensity through an intermediate or transmission media, such as wire lines, a radio carrier, and/or recording means, to a reproducer for audible reproduction.

The primary purpose and objective of the present invention is to enable sound sequences or programs of all types to be reproduced with a dynamic range of the original source despite the restrictions of present-day transmission media.

In the production of audible message matter or programs of this character, as for example, in a radio program, there may be, within the audible range, a variation of as much as 60 decibels between the loudest and softest sound, and, since such variations represent major elements of the artistry put into the production of the program, it is usually desirable that these expressions be preserved or easily controlled so that the envelope of intensity curve or dynamic pattern of the original may be attained in the reproduction.

There are, however, certain mechanical and physical limitations inherent in the particular intermediate media commonly employed, so that it has been necessary for the various industries to adopt make-shift expedients which cause marked and objectionable distortion and dynamic alteration of the reproduced sound. The limitations of the commonly used intermediate media are such that before the varying power impulses or energy created or induced by the audibly produced sound are impressed upon or transmitted to the intermediate media, these impulses must be reduced in intensity at their strongest portions so as not to exceed the permissible maximum capabilities for the particular intermediate media.

While it may be suggested that this undesired modification of the intensity of the sound sequence might be avoided by uniformly (rather than variably) reducing the intensity of the sound-induced impulses, such an expedient cannot be used in practice, since it would decrease the signal-to-noise ratio to such an extent as to render the less intense portions of the desired program unintelligible. This troublesome situation arises from the fact that, in the various commonly used intermediate media, there is a

substantially fixed noise background which must be exceeded by the signal intensity at all times in order to insure intelligibility of the desired impulse or signal. In telephone transmission 10 such noise background is known as line noise; in radio or carrier wave transmission it comprises various types of static as well as noises inherent in the transmitter and receiver; while in recorded programs it is caused by noises mechanically introduced in the recording and the pick-up from the record and is commonly known as surface noise.

Hence the sound engineer must not only reduce the transmitted intensity of the louder portions 15 of the program, but must also increase the transmitted intensity of the softer portions so as to exceed the fixed noise level of the intermediate media. This operational practice, including both increase and decrease of the amplification, is 20 known to members of the profession simply as "squeezing." This necessary variation or squeezing reduces the fidelity of reproduction.

Thus it is found that where the original sound 25 is picked up by a microphone and transmitted electrically by an intermediate media such as a wire line or radio carrier wave, the portions of highest intensity must be reduced, and the portions of lowest intensity must be increased, so that the ratio of maximum to minimum in the 30 energy transmitted to the intermediate media does not exceed 30 decibels. Similarly, when the intermediate media includes the step of recording, the maximum variation of the energy applicable thereto is limited to from 20 to 30 decibels 35 as determined by the method or type of recording employed.

In practice it is found that a large percentage 40 of the programs, selections, or messages which are to be transmitted or recorded for reproduction purposes involve variations in sound-intensity which exceed the capacity or limitations of the intermediate media to be employed. As a result, the sound engineer supervising the recording or transmission of a particular selection 45 or program appropriately reduces the amplification in the sound pick-up system when large-volume portions of the program are being produced. Having thus varied the transmitted sound-intensity to meet the maximum physical 50 limitations of the equipment employed, the engineer has transmitted to the intermediate media a program which does not faithfully represent the original. Hence, the original program or selection, with the contrast, expression and forcefulness which has been so earnestly sought in its

original production, has been lost, and in its place, for reproduction, there is substituted a modified version which lacks, in its vital portions, the artistry and expressiveness of the original.

The resulting dynamic distortion of the reproduced sound sequence has long been recognized as being highly objectionable, and various expedients looking toward reestablishment of the original intensity curve have been widely used and commercially exploited. Such an effort to obtain the desired fidelity of reproduction involved the use of devices known commercially as "expanders," such devices having been incorporated in amplifiers associated with radio receivers, telephone circuits, and in phonographs of various kinds. Such expander devices operated upon the assumed principle that extremely high volume portions of a transmitted sound sequence had originally been suppressed or lowered in intensity, and should, therefore, be expanded or made louder by the reproducer, while portions of low intensity should be made of less intensity upon the assumption that they had been amplified at the outset to over-ride background noise. Such expanders were operative in accordance with and controlled by the transmitted envelope of signal-intensity to produce the supposed correction in the volume of the reproduced sound.

Bearing in mind the fact that the corrective measures or squeezing applied by the sound engineer vary not only with the character of the sound sequence, program or musical selection, but also with the individual preferences of the particular sound engineer, it will be evident that such automatically produced corrective measures could rarely, if ever, result in a truly faithful reproduction. Furthermore, such expanders involve a time-delay action which, in the reproduction of many types of program, produce incongruous results which are apparent even to the most inexpert audience.

In view of the foregoing, a more specific object of the present invention is to provide a new and improved sound system or method and apparatus wherein the corrective changes in amplification initially applied to the sound sequence are automatically and accurately applied in an inverse ratio to the reproducing means so as to cause more faithful reproduction of the original sound sequence.

Another object is to provide a method of sound transmission and reproduction whereby the expansion or reduction of intensity of all or any portion of the reproduced sound may be readily and accurately controlled by the sound engineer to obtain the desired dynamic pattern in such reproduction.

A further and more specific object is to produce a new and improved sound system or method and apparatus which lends itself to ready manipulation to accentuate, vary or emphasize particular sounds of portions of the program which are not capable of proper production in the studio, as for example, a shot or explosion.

Another object is to provide a new and improved sound system or method of sound reproduction wherein there is available at the reproducer for accurate and faithfully patterned reproduction the full range of intensity-variation of 60 decibels.

A further object is to provide a sound system or method of this character wherein mistakes or slight delays of the sound engineer in "squeezing" or expanding the sound pick-up system are

immaterial, whereby to save the expense and delay and improper results which would arise under present-day practice.

Another object is to provide a novel sound system or method wherein the maximum signal-to-noise ratio may be used in all parts of a program, whereby to completely obliterate the objectionable noise background and insure greater fidelity and intelligibility of reproduction. In the application of this phase of the invention to the recording art, there is a marked increase in the useful life of the records, since the usual increase of surface noise with the age of the record becomes immaterial.

Another object is to provide an improved system or method of wire line transmission wherein line noise becomes less important and less troublesome than in prior systems.

A further object is to provide a novel sound system or method adapted for use in carrier wave transmission and capable of more accurately reproducing the original program so far as the variations of sound-intensity are concerned.

Another object is to produce a new and improved method of recording sound.

Another object is to produce a new and improved sound record.

Another object is to produce a new and improved radio receiver.

Another object is to produce a new and improved phonographic reproducer.

Another object is to produce new and improved apparatus for the reproduction of sound in connection with the projection of sound motion pictures.

A general object of the invention is to provide apparatus for carrying out the various methods or systems hereinabove specified.

Other objects and advantages will become apparent from the following description, taken in connection with the accompanying drawing, in which—

Fig. 1 is a block diagram illustrating a preferred form of apparatus embodying the features of the invention.

Fig. 2 is a wiring diagram showing the circuit of an amplifier operable in accordance with the invention.

Fig. 3 is a block diagram illustrating another embodiment of apparatus for use in the practice of the invention.

Fig. 3a is a fragmental illustration of a portion of a reproducer circuit, based on the circuit of Fig. 2, but modified for use in connection with the apparatus of Fig. 3.

In accordance with the present invention, the limitations of the intermediate or transmission media so far as permissible intensity-variations are concerned are rendered immaterial, and the desired correspondence between the dynamic patterns of an original sound sequence and a reproduction thereof is obtained through the use of a variable dynamic control signal, which control signal is preferably created and varied as an incident to and in accordance with the required squeezing of the transduced sound sequence, and is automatically utilized as an incident to the reproduction process to reverse the originally applied squeezing process and thereby restore the original dynamic pattern of the sound sequence.

In Fig. 1 of the drawing an apparatus for carrying out this novel method is illustrated diagrammatically by means of a block diagram, the various elements of the system being identified

thereon in a generic sense because of the wide range of usefulness of the system. Thus the system includes a transducer such as a microphone 10 connected by a transmission path 11 to an amplifier 12 whereby electrical vibrations induced by the desired sound sequence are amplified for transmission over a path 13 to an intermediate transmission media 14. This intermediate media may be any one of the several known types, such as recording and re-pickup, carrier wave, wire lines, or combinations thereof, whereby the transduced sound energy is delivered to a reproducing means. The reproducing means herein shown is in the form of a speaker 15 connected through volume modifying means such as an amplifier 16 to the intermediate media 14.

Sound sequences are commonly transmitted and reproduced with a system including those elements thus far specifically enumerated, but by reason of the limitations as to maximum permissible intensity-variation inherent in the various types of intermediate media 14, it is often impossible to attain true dynamic correspondence between the original and reproduced sound sequence. This objectionable limitation of conventional sound systems is overcome by the present invention through the employment of a varying corrective signal the character of which is determined automatically as an incident to the required squeezing of the sound sequence, and which signal is automatically utilized in the reproduction process to restore the original dynamic pattern of the sound sequence.

This end is attained through the use of a control signal having characteristics distinguishable from those portions of the sound sequence which are to be audibly reproduced. Present-day standards provide that reproducers which will reproduce frequencies up to 8000 cycles per second are to be termed "high fidelity" reproducers, and upon this basis, any frequency beyond 8000 cycles may be used as a control signal. Hence, for purposes of illustration, I have chosen 9000 cycles as the control frequency to be employed, and have inserted in the transmission path 11 adjacent the microphone 10 a filter 20 whereby all sound-induced frequencies above 8000 cycles are filtered from the circuit.

The desired control signal is, in the system herein shown, generated by an oscillator 21 set for the generation of 9000 cycle current, which is fed through a filter 22 sharply tuned to pass only 9000 cycle current to an attenuator 23 which limits the voltage to be transmitted. This uniform 9000 cycle control signal is passed through a variable resistance 24 to the transmission path 11 which resistance 24 is arranged in parallel with a volume control 25 in the path 11. Separate volume controls 24 and 25 are used in the present instance, but the same control could be used by correspondingly altering certain features of the reproducer as will be hereinafter explained. The two control elements 24 and 25 are, however, operated in unison by a common volume control element 26 which is so connected that when the intensity of the transduced sound energy is reduced, the transmitted intensity of the control signal is increased in a predetermined ratio. Similarly, when the intensity of the transduced sound energy is increased, as when it is desired to increase the signal-to-noise ratio, the transmitted intensity of the control signal is reduced in accordance with the predetermined ratio.

Hence, two related signals are produced, one of which constitutes a desired audio signal, modi-

fied or squeezed to make it conform with the limitations of the intermediate media, and the second of which constitutes a distinguishable control signal timed in relation to the audio signal and indicative of the varying corrective amplification which must be applied to the squeezed audio signal in its reproduction in order to restore the original dynamic or amplitude pattern. While individual transmission of these two related signals is possible, I prefer to combine the two or to form a composite signal which is amplified and transmitted to the intermediate media 14.

After the composite signal has been transmitted through the intermediate media 14, the two distinguishable elements or signals are separated so that the audio signal may be used to reproduce the desired sound while the control signal may be employed to govern the dynamic or amplitude pattern of such reproduced sound. This end is attained in the present illustrative embodiment by feeding the composite signal from the intermediate media 14 along two parallel paths 27 and 28, one path 27 of which embodies a filter 30 which passes the desired audio signal only, that is, the frequencies from, say 30 cycles, to 8000 cycles, while the other path 28 includes a filter 31 which passes only the control signal of 9000 cycles. The separate signals are then applied to the amplifier 16, the desired audio signal being applied so as to amplify the transduced sound energy while the control signal is passed through a rectifier and filter 33 and the resulting direct current is then applied so as to vary the amplification or modify the volume of the transduced sound energy in an opposite ratio to the originally applied squeezing. Hence the transduced sound energy acts upon the speaker 15 to reproduce the sound sequence in a dynamic or amplitude pattern corresponding with the original.

While the system has been herein described as attaining exact correspondence between the dynamic patterns of the original and reproduced sound sequence, it is to be understood that such exact correspondence is not desired in every instance, and that the system of the present invention is highly flexible in enabling the sound engineer to obtain practically any desired dynamic pattern in the reproduction. Thus, the present invention may be employed to expand or reduce all or any desired portion of a sound sequence, and such variation may be in any desired ratio within practical limits. This end may be attained in a variety of ways, as for example, by insertion of a variable resistance in the control signal path between the control 24 and the path 11; or by adjustment of the attenuator 23; or by varying the type or characteristics of the control 24; or the reproducer may be designed to give a similar controlling action by inserting a variable resistor between the rectifier 33 and the amplifier 16.

When the intermediate media includes the step of recording, the composite signal passes from the amplifier 12, and by means of the properly set switch 35, along the path 36 to a recording means such as a phonographic recorder 37. The present invention contemplates, of course, that the composite signal, or the two separate signals, could be applied by known means to other forms of recording means; and upon the same or related sound tracks. Since such applications of the present invention involve merely variations of known apparatus in the manner

taught by the present disclosure, the illustration and description will herein be confined to phonographic recording upon a disk record 38 supported by a conventional turntable 39 (Fig. 3). Hence, with the arrangement, the composite signal is impressed upon the record 38.

When this record is placed upon turntable 40 (Fig. 2) of a phonographic reproducer, this composite signal is picked up by the electrical pickup 41 and transmitted along the path 42 through the properly set switch 43, to the reproducing apparatus. One form or embodiment of apparatus suitable for reproducing the composite signal thus formed with the apparatus of Fig. 1 is shown in detail in Fig. 2, this particular reproducer being shown as deriving its signal from the electrical phonographic pickup 41, but being capable of operative association with any of the various types of intermediate media.

In the reproducer of Fig. 2 the composite signal energy derived from the intermediate media is transmitted through a transformer coupling 44, and from the high side of the transformer secondary is fed along the two parallel paths 27 and 28, wherein the desired audio signal and the control signal are separated as explained in connection with Fig. 1. The filter 36 shown in the path 27 in Fig. 2 is constructed and connected in accordance with known principles to attenuate the 9000 cycle control signal and to pass the audio frequencies which are to be reproduced, such for example as those frequencies between 30 cycles and 8000 cycles, and this audio signal is impressed through a wire 45 upon the normal control element or amplifier grid 46 of a thermionic amplifier tube 47. The tube 47 constitutes one of many possible embodiments of the amplifier 16 described in connection with Fig. 1, and in the present instance I have illustrated this tube as being of the commercially known 6L7 type. This tube serves as a volume modifying means, and it will be understood that the same ultimate end might be attained by many types of apparatus, such for example, as a thermionic pad whereby the sound-intensity is variably attenuated after a relatively large and uniform initial amplification, rather than variably amplified in the strict sense. The plate circuit of the amplifier 47 is conventionally connected to leads 48 which may be connected to a further stage of amplification, or to a reproducer such as the speaker 15 of Fig. 1.

The other path 28 has a sharply tuned filter 31 associated therewith as shown in Fig. 2, so that the frequencies other than the 9000 cycles control signal are filtered off to ground and the control signal is passed along a conductor 28' to the amplifier grid 50 of a thermionic amplifier 51. This control signal amplifier 51 may be formed by a conventional 6F6 tube, and its plate 52 is transformer coupled at 53 to the control frequency rectifier and filter 33. The rectifier tube is herein shown as being of the conventional 6H6 type and is indicated by the numeral 54. The connections of the two diodes of the tube 54 are such as to provide a full wave rectifier, and there is included a filter or condenser 55, whereby the output of the rectifier is a continuous direct current the varying intensity of which represents a function of the varying intensity of the originally transmitted control signal.

The output circuit of the control signal filter and rectifier 33 includes a load resistor 56, and the necessary portion of the rectified filtered voltage is taken from this load resistor 56 and is impressed through a conductor 57 upon the injection

element or grid 58 of the audio-signal amplifier 47. When the control signal has been formed by the system illustrated in Fig. 1, the load resistor 56 is located in the positive portion of the circuit, that is, in the cathode lead. Thus when an increase of intensity of the rectified and filtered control signal indicates that an increased amplification of the audio signal is required, this increased positive voltage is applied to the conductor 57 and acts to bring about the necessary increase of amplification in the tube 47. This tube 47, as herein shown, exhibits its greatest amplification when the injection grid 58 is least negative, and its amplification decreases as the negative potential on the injection grid is increased. Hence the lower side of the load resistor 56 is connected, as indicated at 58, to a source of relatively high negative voltage, say, minus 40 volts; and as a result the injection grid 58 is normally biased negatively to such an extent as to render the tube 58 insensitive. This normally blocked condition of the tube 58 is variably offset by the positive portion of the rectified and filtered control signal applied through the conductor 57, so as to transmit the audio signal with the desired or restored dynamic pattern. The absence of a control signal results, of course, in the blocking of the tube 47, and hence there can be no audible reproduction of background noise at such times.

In Figs. 3 and 3a of the drawing I have illustrated alternative forms of apparatus embodying the invention, and with these alternative forms the variation of the control signal is in an inverse ratio to the variation employed in the structure of Figs. 1 and 2. Thus in the system shown in Fig. 3, the transduced sound energy passes along the path 11, through the filter 26, volume control 25, and amplifier 12 to the intermediate media, such as the recording means 37, all constructed and related in the same manner as in Fig. 1. The control frequency is generated by a similar oscillator 21 and passes through the filter 22 and attenuator 23. In the system of Fig. 3, however, the same volume control 25 is used for varying both the audio signal and the control signal, and hence the control frequency is conducted along a path 23' from the attenuator 23 to a point between the filter 26 and the volume control 25.

This reversal of the control signal variations requires correspondingly different application of the control signal to the injection grid 58. This end may be attained by modification of the rectifier circuit of the structure shown in Fig. 2, such a modification being shown in detail in Fig. 3a of the drawing. Thus the rectifier tube 54 is connected as a full wave rectifier with the condenser 55' and the load resistor 56' connected in the negative portion of the circuit, or in the plate lead. As a result, a negative potential is impressed on the injection grid 58 and the intensity of this negative potential is a function of the intensity of the control signal. Since the load resistor 56' is grounded at 59', the injector grid 58 has zero potential when there is no control signal present; and it is by the increasing application of negative bias on the grid 58 that the amplification of the tube 47 is reduced. Hence, where a reduction in the control signal intensity signifies the need for expansion of the audio signal, the reduced negative potential on the grid 58 attains this desired end.

The foregoing description has been confined to the application of the present invention where

the intermediate transmission media includes various common types of recording, but it will be evident that the present invention is likewise applicable to the other types of intermediate media 14 as indicated diagrammatically in Fig. 1 of the drawing. Thus, it will be evident that through appropriate adjustment of the switches 35 and 43 of Fig. 1, the sound would be transmitted by carrier wave as indicated at 61, or by wire lines as indicated at 62.

In constructing the present apparatus the normal intensity level of the control frequency is so adjusted that in normal variation in accordance with the squeezing applied to the audio signal, the range of intensity variation in the control signal will be within the capabilities of the intermediate media. In the reproducer, the adjustment of the intensity of the rectified control voltage applied to the injection grid 58 is attained through variation of the point of connection of the conductor 57 with the load resistor 56, or by other conventional expedients such as the variation of the normal bias applied at 60, or by variation of the amplification in the control signal amplifier 51. In any event, the adjustment of the control impulse is such that the reproduction of any particular portion of a sound sequence is of an intensity equaling or bearing the desired intensity relation to the corresponding portion of the original sound sequence.

From the foregoing description it will be apparent that the present invention provides a method of and apparatus for sound transmission and reproduction whereby inherent limitations in the transmission capabilities of various types of intermediate transmission media such as carrier wave, wire lines or recording systems, are rendered immaterial, thereby to endow the reproduced sound sequences with accurately patterned and controlled dynamic characteristics heretofore unattainable.

It will also be evident that the present invention provides a new and improved sound record having greatly improved reproduction characteristics as well as an increased useful life.

In addition, the present invention provides new and improved methods of and apparatus for sound transmission and reproduction by carrier wave as well as wire line transmission, and in each instance the invention obviates many objectionable features of prior facilities.

I claim as my invention:

1. The method of obtaining correspondence between the dynamic patterns of an audibly produced sound sequence and an audible reproduction of such sequence reproduced after transmission of a transduced representation of the sequence through an intermediate media requiring squeezing of the sound-induced representations to bring such representations within the intensity-variation capabilities of the media, which consists in transmitting in timed relation to such representations a corrective signal which, as an incident to the squeezing of the sound induced representations, has been varied in intensity in predetermined ratio to such squeezing so as to be indicative of the expansion or reduction required in the intensity of the transmitted representations to restore the original dynamic pattern thereof, and automatically utilizing the corrective signal to expand or reduce such representations as an incident to the audible reproduction of the sound sequence.

2. The method of obtaining correspondence between the dynamic patterns of an audibly pro-

duced sound sequence and an audible reproduction of such sequence reproduced after transmission of a transduced representation of the sequence through an intermediate media requiring squeezing of the sound-induced representations to bring such representations within the intensity-variation capabilities of the media, which consists in transmitting in timed relation to such squeezed representations a corrective signal which, as an incident to the squeezing of the sound induced representations, has been varied in intensity in predetermined ratio to such squeezing so as to be indicative of the expansion or reduction required in the intensity of the transmitted representations to restore the original dynamic pattern thereof.

3. The method of transmitting sound from a sound pickup system to an intermediate media having limited capacity as to intensity-variations which consists in squeezing the sound-induced energy in the sound pickup system to meet the capacity of the intermediate media, simultaneously varying the intensity of a continuous control signal to vary the intensity of the control signal in accordance with and in predetermined relation to such squeezing, and transmitting said squeezed sound energy and said continuous control signal to the intermediate media in predetermined timed relation to each other.

4. The method of transmitting through an intermediate media having a limited capacity as to intensity-variations a program squeezed to meet such limitations which consists in simultaneously transmitting through the same media a continuous control impulse varying in intensity in accordance with and in predetermined ratio to the squeezing applied to the transmitted program.

5. The method of transducing and transmitting through an intermediate media a sound sequence involving sound-intensity variations exceeding the limits permissible in said intermediate media which consists in reducing and varying the intensity of the more intense portions of the sound-induced impulses transmitted to the intermediate media as required to bring such portions within the transmitting capacity of said media and simultaneously transmitting a continuous distinguishable control impulse which has been varied in intensity in predetermined ratio to such reduction and variation as an incident to such reduction and variation.

6. The method of avoiding unintelligibility in transmitted and reproduced sound due to background noise in the intermediate media which consists in applying a squeezing operation to vary the amplification of the sound-induced energy at the transmitting means to transmit such energy at the maximum signal-to-noise ratio obtainable with the particular intermediate media, and inversely and automatically varying the ultimate amplification at the receiving and reproducing means to restore the original intensity curve to the reproduced sound.

7. The method of sound transmission through an intermediate media having limited transmission capabilities in respect to the range of permissible intensity-variation which consists in varying the amplification at the point of sound pickup so as to maintain the intensity of the transmitted sound-induced energy at substantially the maximum permissible intensity at all times and transmitting simultaneously a continuous control impulse of a distinguishable frequency and varying in intensity in accordance

with the variations in the amplification of the sound-induced energy.

8. In a sound reproducing mechanism, the combination of a sound record having a sound track bearing a composite representation of a desired sound sequence within a predetermined range of frequencies to be reproduced and a control signal of a distinguishable frequency, means sensitive to said composite representation to produce electrical vibrations corresponding therewith, means for separating the electrical vibrations representing said control signal from the electrical vibrations representing said desired sound sequence, and amplifying and reproducing means operated by the electrical vibrations representing said sound sequence to reproduce said sound sequence, and means forming part of said amplifying and reproducing means and controlled by said control signal to govern the intensity of the reproduced sound sequence.

9. A sound system having a sound pickup means including a filter operable to limit the range of frequencies transmitted thereby, a volume control governing the transduced output of said pickup means, and means for introducing into the output of said pickup system a signal of a frequency outside of said range and varying in intensity under the governing action of said volume control.

10. In a sound system, the combination of an electrical sound pickup means having a transmission line connected thereto, filter means in said line for limiting the range of frequencies transmitted thereby, a frequency generator operable to produce a frequency outside of said range and connected to said line beyond said filter means, and a volume control operatively associated with said line beyond the point of connection of said frequency generator.

11. In a sound system the combination of a transducer and an intermediate transmission media to receive and transmit the transduced sound, a frequency generator operable to supply a control current of predetermined frequency, and circuit means operatively connecting said transducer and said frequency generator to said intermediate transmission media and including volume control means operable by a single control element to vary simultaneously and in predetermined relation the intensity of the transduced sound and the control current.

12. The method of producing a sound record which consists in combining sound-induced vibrations within a predetermined frequency range to be reproduced with a constant intensity signal of a frequency outside said range to form a composite signal, variably modifying the intensity of the composite signal to maintain the same within the limits of intensity-variation allowable with the particular recording medium, and applying the modified composite signal to the recording medium.

13. The method of producing a sound record which consists in creating electrical vibrations corresponding to the sound to be recorded, creating a continuous series of electrical vibrations of uniform intensity and of a frequency outside the range of frequencies of the sound-induced vibrations, correspondingly reducing the intensity of all of such vibrations as required to bring the intensity-variation of the sound-induced vibrations within the recording limits of the recording medium being used, and simultaneously applying all of said vibrations to the recording medium.

14. The method of producing a sound record which consists in creating electrical vibrations corresponding to the sound to be recorded, creating a continuous series of electrical vibrations of uniform intensity and of a frequency outside the range of frequencies of the sound-induced vibrations, correspondingly reducing the intensity of all of such vibrations as required to bring the intensity-variation of the sound-induced vibrations within the recording limits of the recording medium being used, and applying such sound-induced vibrations and the other vibrations to the recording medium in a predetermined relation to each other.

15. The method of producing a sound record of a sound sequence involving intensity-variations requiring squeezing of the sound-induced energy before application thereof to the recording medium which consists in applying to the recording medium in timed relation to the record of the sound-induced energy a continuous control impulse which, as an incident to the squeezing of the sound induced representations, has been varied in intensity in predetermined ratio to such squeezing so as to be indicative of the expansion or reduction required in the reproduction process to attain the desired dynamic pattern in such reproduction of the sound sequence.

16. The method of producing a sound record which consists in variably reducing the stronger portions of a desired sound sequence before they are applied to the recording medium and simultaneously applying to the recording medium a continuous control signal of distinguishable frequency and varying in intensity in a predetermined ratio to the variable reduction of the intensity of the sound sequence.

17. The method of producing a sound record to avoid the usual surface noise which consists in varying the amplification of the sound-induced energy before it is applied to the record so as to maintain a favorable signal-to-noise ratio at all times, and simultaneously applying to the record a continuous control impulse of distinguishable frequency and varying in intensity in accordance with the variations in the amplification of the sound-induced energy.

18. In a process of recording an audibly produced sound sequence and then audibly reproducing the same, the method of obtaining correspondence between the dynamic patterns of the audibly produced and the audibly reproduced sound sequence which consists in squeezing the sound sequence to bring it within the permissible range of intensity variation and simultaneously recording in timed relation to the recording of the squeezed sound-induced energy a corrective signal which, as an incident to the squeezing of the sound sequence, has been varied in intensity in predetermined ratio to such squeezing so as to be indicative of the expansion or reduction required in the recorded indications of the sound-induced energy to restore the original dynamic pattern thereof, and automatically utilizing the corrective signal to expand or reduce the volume of the reproduced sound sequence as an incident to the reproduction thereof.

19. A sound record having sound track means thereon representing in fixed timed relation a desired sound sequence which is to be audibly reproduced and which has been squeezed to meet the limitations of the record insofar as intensity variations are concerned and representing a continuous control impulse which has been varied in its intensity in accordance with and as an inci-

dent to the squeezing of the desired sound sequence and which is applicable as an intensity-correction to the audibly reproduced desired sound sequence in the audible reproduction thereof.

20. A sound record having sound track means thereon representing vibrations induced by a desired sound sequence and which has been varied as to amplitude so as to maintain a favorable signal-to-noise ratio at all points, and additional means on said record in predetermined relation to said sound track means and distinguishably representing a varying intensity-correction which has been varied in its intensity as an incident to and in predetermined ratio to said variation of the desired sound sequence so as to represent a corrective to be applied in the reproduction process to obtain in the reproduction a dynamic pattern corresponding to the dynamic pattern of the original sound sequence.

21. The method of carrier wave communication which consists in variably reducing the stronger portions of a desired sound sequence before they are impressed upon the transmitted carrier wave and simultaneously impressing upon the carrier wave a continuous control signal of distinguishable frequency and varying in intensity in predetermined ratio to said variable reduction of the intensity of the sound sequence.

22. The method of carrier wave transmission of sound-induced electrical vibrations lying within a given range of frequencies to be audibly reproduced which includes the application of such vibrations and also electrical vibrations of a distinguishable frequency to the carrier wave while simultaneously varying the intensity of all of said vibrations to meet transmission limitations as to dynamic range.

23. The method of carrier wave communication which consists in forming a composite signal consisting of a desired signal and a control signal of distinguishable frequencies varying the intensity of the composite signal as required to bring the intensity-variation of the composite signal within the maximum capabilities of the carrier, and impressing the resulting composite signal on the carrier wave to modulate the same.

24. The method of carrier wave communication which includes the steps of forming a composite signal consisting of a desired signal and control signal of distinguishable frequencies, varying the intensity of the composite signal so as to bring the composite signal within the range of permissible intensity-variation for the carrier, impressing the resulting composite signal on the carrier wave to modulate the same, receiving said carrier wave, separating the desired signal and the control signal, applying the desired signal to an amplifier and thence to a reproducer, and applying the control signal to the amplifier to produce in the reproduced signal an intensity-curve corresponding to a predetermined function of the intensity-curve of the original desired signal.

25. The method of wire line transmission which consists in transmitting in timed relation to the desired audio signal which has been squeezed to meet wire line transmission limitations, a variable control signal which, as an incident to the squeezing of the desired signal, has been varied in intensity in predetermined ratio to the squeezing so that the intensity of said control signal is indicative of a volume correction to be applied to such audio signal to restore the original intensity-curve of the audio signal, and automatically

cally correcting the volume of the audio signal in its reproduction in accordance with the variations in said control signal.

26. In a sound reproducing mechanism, the combination of a sound record having a sound track bearing, in predetermined positional relationship, representations of a desired sound sequence within a predetermined range of frequencies to be reproduced and which has been varied in intensity with respect to the original audibly produced sound sequence to meet the limitations of the record, and a control signal of a distinguishable frequency wherein said control signal has been varied in predetermined ratio to said variations in the intensity of the desired sound sequence, means sensitive to said representations to produce electrical vibrations corresponding therewith, and amplifying and reproducing means operated by the electrical vibrations representing said sound sequence to reproduce said sound sequence, and means forming part of said amplifying and reproducing means and controlled by said control signal to govern the intensity of the reproduced sound sequence.

27. The method of carrier wave communication which consists in impressing upon the carrier wave, in timed relation to the impression of a desired signal which has been squeezed to meet the permissible intensity-variation limitations of the carrier wave, a variable control signal which, as an incident to the squeezing of the desired signal, has been varied in intensity in a predetermined ratio to the squeezing of the desired signal so that the intensity of said control signal is indicative of a volume correction to be applied to such desired signal to restore the original intensity curve of the desired signal.

28. The method of carrier wave communication which consists in impressing upon the carrier wave, in timed relation to the impression of a desired signal which has been squeezed to meet the permissible intensity-variation limitations of the carrier wave, a variable control signal which, as an incident to the squeezing of the desired signal, has been varied in intensity in predetermined ratio to such a squeezing so as to be indicative of a volume correction to be applied to such desired signal to restore the original intensity curve of the desired signal, and automatically correcting the volume of the desired signal in its reproduction in accordance with the variations in said control signal.

29. In a sound reproducing mechanism, the combination of a sound record having a sound track bearing representations of a desired sound sequence within a predetermined range of frequencies to be reproduced and which has been squeezed so as to vary its intensity with respect to the original audibly produced sound sequence to meet the limitations of the record, and also having on said sound track, in a predetermined positional relation to said representations of said desired sound sequence, additional representations of a control signal of a predetermined distinguishable frequency wherein said control signal has been varied in intensity in predetermined ratio to said variations in the intensity of the desired sound sequence, means sensitive to said representations to produce electrical vibrations corresponding therewith, a first amplifier and an associated reproducing means operated by said electrical vibrations representing said sound sequence to reproduce said sound sequence, and control means comprising a second amplifier, a circuit to said second amplifier in-

cluding filter means operable to pass the electrical vibrations corresponding to said control signal from said sensitive means to said second amplifier, a full-wave rectifier operatively coupled to said second amplifier, and means for applying the full wave rectified output of said full-wave rectifier to said first amplifier to restore the original dynamic pattern to the reproduction of the desired sound sequence.

30. In a sound reproducing mechanism adapted for use with a sound record having a sound track bearing representations of a desired sound sequence within a predetermined range of frequencies to be reproduced and which has been squeezed so as to vary its intensity with respect to the original audibly produced sound sequence to meet the limitations of the record, and also having on said sound track, in a predetermined positional relation to said representations of said desired sound sequence, additional representations of a control signal of a predetermined distinguishable frequency wherein said control signal has been varied in intensity in predetermined ratio to said variations in the intensity of the desired sound sequence, said sound reproducing mechanism comprising means sensitive to said representations to produce electrical vibrations corresponding therewith, a first amplifier and an associated reproducing means operated by said electrical vibrations representing said sound sequence to reproduce said sound sequence, and control means comprising a second amplifier, a circuit to said second amplifier including filter means operable to pass the electrical vibrations corresponding to said control signal from said sensitive means to said second amplifier, a full-wave rectifier operatively coupled to said second amplifier, and means for applying the full-wave

rectified output of said full-wave rectifier to said first amplifier to restore the original dynamic pattern to the reproduction of the desired sound sequence.

5 31. In a sound reproducing mechanism adapted for use with a sound record having a sound track bearing representations of a desired sound sequence within a predetermined range of frequencies to be reproduced and which has been squeezed so as to vary its intensity with respect to the original audibly produced sound sequence to meet the limitations of the record, and also having on said sound track, in a predetermined positional relation to said representations of said desired sound sequence, additional representations of a control signal of a predetermined distinguishable frequency wherein said control signal has been varied in intensity in predetermined ratio to said variations in the intensity of the desired sound sequence, said sound reproducing mechanism comprising means sensitive to said representations to produce electrical vibrations corresponding therewith, a first amplifier and an associated reproducing means operated by said electrical vibrations representing said sound sequence to reproduce said sound sequence, and control means comprising a second amplifier, a circuit to said second amplifier including filter means operable to pass the electrical vibrations corresponding to said control signal from said sensitive means to said second amplifier, a rectifier, an untuned coupling between said second amplifier and said rectifier, and means for applying the output of said rectifier to said first amplifier to restore the original dynamic pattern to the reproduction of the desired sound sequence.

JAMES E. DICKERT.
